UNITED STATES PATENT OFFICE.

CHARLES W. MABEY, OF INDIANAPOLIS, INDIANA, ASSIGNOR TO CENTURY ELECTRIC COMPANY, OF INDIANAPOLIS, INDIANA, A CORPORATION.

DESIGN FOR A DISPENSER FOR BEVERAGES.

49,153.

Specification for Design.

Patented June 6, 1916.

Application filed April 6, 1915. Serial No. 19,561. Term of patent 7 years.

To all whom it may concern:

Be it known that I, CHARLES W. MABEY, a citizen of the United States, residing at Indianapolis, in the county of Marion and State of Indiana, have invented a new, original, and ornamental Design for a Dispenser for Beverages, of which the following is a specification, reference being had to the accompanying drawing, forming a part hereof.

Figure 1 is a horizontal section showing the contour of the upright portions of the dispenser for beverages. Fig. 2 is a perspective view of the dispenser for beverages, showing my design.

I claim:

The ornamental design for a dispenser for beverages as shown.

CHARLES W. MABEY.
